(57) **CLAIM**

I claim the ornamental design for a body part dressing, as shown and described.

DESCRIPTION

FIG. 1 is a perspective view of a body part dressing showing my new design in a first in-use folded position.

FIG. 2 is a front plan view of the ornamental design of FIG. 1.

FIG. 3 is a side view of the ornamental design of FIG. 1.

FIG. 4 is a top plan view of the ornamental design of FIG. 1.

FIG. 5 is a bottom view of the ornamental design of FIG. 1.

FIG. 6 is a top plan view of my ornamental design in an unfolded pre-use position.

FIG. 7 is a front view of the ornamental design of FIG. 6, showing placement of a closure means.

FIG. 8 is a front plan view of the ornamental design of FIG. 7 in which the central portion thereof has been opened for use.

FIG. 9 is a perspective view of FIG. 8.

FIG. 10 is a perspective view of a partially closed position about mid way between those of FIGS. 9 and 1.

FIG. 11 is a front plan view of my ornamental design in an optional first pre-use folded position.

FIG. 12 is a front plan view of my ornamental design in an optional second pre-use folded position; and,

FIG. 13 is a front plan view of my ornamental design in an optional third pre-use folded position.

The broken lines shown of body part dressing is included for the purpose of illustrating environmental structure is used and forms no part of the claimed design.
